180,000

FURNITURE LEG

Forest Wilson, Chicago, Ill.

Application March 13, 1956, Serial No. 40,585

Term of patent 3½ years

(Cl. D33—14)

Fig. 1 is a perspective view of a furniture leg embodying my new design;

Fig. 2 is a side elevational view of the furniture leg of Fig. 1; and

Fig. 3 is a top view of the furniture leg of Fig. 1.

I claim:

The ornamental design for a furniture leg, substantially as shown.
